UNITED STATES PATENT OFFICE.

JEAN BAPTISTE ADOLPH LA JEUNESSE, OF ALAMEDA, CALIFORNIA.

SYRINGE.

Application filed September 29, 1906, Serial No. 336,774. Renewed July 17, 1924.

To all whom it may concern:

Be it known that I, JEAN BAPTISTE ADOLPH LA JEUNESSE, a citizen of the United States, and a resident of the city and county of Alameda, in the State of California, have invented a new and useful Syringe, of which the following is a specification, reference being had therein to the accompanying drawing.

10 The invention relates to a fountain syringe and means for mechanically operating the same. It aims to provide a simple and efficient apparatus whereby enemas can either be administered or taken comfortably in different positions.

15 In the drawing, Figure 1 is a side elevation of the syringe combined with a pressure device specially adapted for working it in a vertical position; Fig. 2 is a perspective view representing part of a bedstead to the foot of which the said pressure device and syringe are attached; Fig. 3 is a similar perspective view of the pressure device separate from the syringe; Fig. 4 is another 20 perspective view showing a seat that may be used in operating the pressure device; Fig. 5 is a detailed view of an improved form of nozzle connected with the spout of the syringe; and Fig. 6 is a perspective view 25 illustrating the combined syringe and pressure device, with the said seat superimposed upon the latter fitted for use in a horizontal position.

30 The letter A represents a fountain syringe designed to hold hot or cold water, plain or medicated. For convenience in suspending it from a primary support, the bag of this syringe is provided at its bottom with a ring C.

35 The pressure device, above mentioned, consists of two members, preferably in the form of boards F, G, secured to opposite faces of an end block E, which serves both as a spacer and a closure. The board F constitutes the bottom of the device, and the block E is fastened to and across one end of it by screws, or in any other suitable manner. The board G forms the top of the device. It is made shorter than the board F by the 40 width of the block E, to the upper inner edge of which it is joined by a pair of butt-hinges L, L². Being thus hinged, the board G may be lifted and turned back to expose and give ready access to a hook D, which is 45 screwed into the adjacent inner side of the

block E. This hook is adapted to pass through the aforesaid ring C of the fountain syringe and hold the latter to and within the pressure device. The hinging also enables the top board G to act as a lever 60 when weight or pressure is put upon it, thereby causing the water to flow from the supplying bag of the syringe accordingly.

The top part of the block E and the adjoining surface of the board G are both 65 covered with felt cloth, as indicated at E² and G² in Figs. 2 and 3. This cloth may be glued on or otherwise fastened in place, but in any case it is laid over the pressure device so as to cover entirely the outwardly 70 turned hinges L, L² thereof, besides the block and top board, after the manner exemplified in the two figures last named. Applied in this way, the cloth not only imparts a certain finish to the device, but it further affords a soft and smooth surface for the bare 75 feet of a person to press upon when taking an enema in a reclining position.

H designates a nozzle or rectal tube (hereinafter more fully described) which is fitted 80 in the outer end of a flexible tube I, connected at its inner end with a nipple J, screwed into the spout of the fountain syringe. See Figs. 2, 5 and 6.

K represents an eye-screw driven into the 85 closed end of the pressure device, preferably in the middle of the outwardly exposed side of the block E. This eye-screw supplies the means wherewith the apparatus can be held vertically for the purpose of either taking or 90 administering enemas while the subject of the treatment is in bed. To this end, the water-bag or fountain syringe A is hung, as indicated in Fig. 1, on the hook C within the pressure device, and the latter is suspended 95 from a transverse member of the bedstead by means of a cord or the like passed through the eye of the screw, as illustrated in Fig. 2. It is understood that, with the apparatus thus mounted, the user thereof can place either foot on the cloth-covered board G and regulate for himself the flow of water from the fountain syringe according to the pressure desired. A nurse or other attendant could operate the pressure device 100 manually, while in the same position, if the patient lying down were too ill to work it in person. In the latter case, however, it is preferable to detach the apparatus from the bedstead, and place it where the operator 105 110

can use it to best advantage, by working the pressure device in any way that is found most convenient.

A seat M, consisting mainly of a separate board of about the same length and width as either of the boards F or G pertaining to the pressure device, is employed in connection therewith, to enable a person to take an enema in a sitting position. The board M 5 is fastened, near one end thereof, to a transverse support B, by screws M², as seen in Fig. 4. Preferably, this support consists of a narrow board rounded at its lower edge B², which is made to bear directly upon the 10 cloth-covered part of the block E. The seat extends inwardly therefrom above the hinged end of the board G, and rests substantially in a horizontal position upon the free end of the latter when raised by the 15 bag or fountain syringe A filled with water, as Fig. 6 indicates. The supporting board B, it will be observed, adapts itself by its rounded edge to the rocking motion of the seat when the pressure device is in operation 20 and the bag or fountain syringe therein is being emptied of its contents.

In the seat M, above described, there are 25 holes N and O, of different diameters, but interconnected by a slot Q. The larger opening N admits of the passage therethrough of the nozzle H, previously mentioned, which has a relatively thin stem R enabling it to be slid over, by way of the slot Q, into the small opening O. When thus inserted, so 30 as to project upwardly as shown in Fig. 6, the nozzle stands substantially perpendicular to the seat, along the median longitudinal line thereof, in position for a person to take the enema while sitting down. By 35 preference, the smaller hole O is located as close as practicable to the free end of the seat, so that the upstanding nozzle will be presented for use at the point nearest to the center of the bulging portion of the 40 fountain syringe filled with water, that is, in the distended condition depicted in Figs. 45 1 and 6.

The aforementioned nozzle H may be 50 made of rubber or other suitable material. If intended to be employed in connection 55 with the seat M as just described, it is preferably formed as illustrated in Fig. 5, where it appears as provided with small, staggered holes S at the sides, through 55 which the water passes out in fine sprays, but it is imperforate and rounded at its outer end T. Above the stem R before referred to, the nozzle has a flange U, the upper part of which is curved in the manner 60 indicated. From this flange to the outer end T the nozzle is of an upwardly increasing diameter as illustrated. The underside of the flange is flat and thereby adapted to be seated over the small hole in the board 65 M. The stem R then becomes lodged in the

hole O directly under the flange. This stem is bent sidewise to form an elbow having opposite curves W, X, and a straight lateral extension Y, over which the flexible tube 70 I is slipped. The outer end of the extension is somewhat enlarged, as at Z, to keep the tube from sliding off. The elbow prevents kinking of the tube, which connects the enlarged part Z of the extension Y with the nipple J at the spout of the fountain syringe, 75 the nozzle being turned to suit while the tube is passed above the upper board G and under the seat M of the pressure device.

Several advantages are derived from the use of the combined spacer and closure, hereinbefore referred to as being formed by the block E at one end of the boards or pressure members F, G. The element E is placed transversely of these pressure members in such a manner as to space them one from the other in two different ways, to wit, intermediately and longitudinally. The intermediate spacing provides a normal clearance between the pressure members, which are thereby kept at the requisite distance 80 apart for the insertion and operation of the fountain syringe. Spacing the members in a longitudinal direction brings the upper one forward of the element E, to which it is hinged and where it finds a fulcrum in 85 bearing upon the syringe during the pressing operation. The closure holds the means for anchoring the syringe within the pressure device, as well as for suspending the latter from a primary support. It enables 90 the syringe to be centered without risk of being crushed or chocked between the pressure members; it also prevents garments, bed-clothes, and the like from being caught by the opposed ends of the members at the 95 hinge, as would happen if they were connected together end to end as in antiquated constructions; and it further protects the syringe against dust, etc., when kept in a suspended position. Other advantages of the 100 spacing and closing element E, and of the cloth E², G², covering it together with the hinged member G, will be quickly discerned 105 by experts in the art to which the present invention appertains.

I claim:

1. The combination with a fountain syringe, of a pressure device including a supporting board, a block secured to one end thereof, a hook suspending the syringe from said block, a surface board hinged to the latter so as to afford a leverage upon the syringe, and means enabling said device with the syringe therein to be maintained in a suspended position.
2. The combination with a fountain syringe, of members adapted to be moved one toward the other so as to press the syringe therebetween, an end closure for said members, means for anchoring the

115

120

125

130

syringe to said closure, and a suspension element on the latter whereby the syringe may be held in an inverted vertical position while under pressure.

5. 3. The combination with a fountain syringe, of a pressure device including a support for the syringe to bear upon, a spacer at one end thereof, means for attaching the syringe to the inner side of said 10 spacer, a member held to the latter by an

outwardly opening hinge enabling it to be worked as a lever upon the syringe, and a cover on the spacer and said member preventing contact of exterior objects with said hinge.

JEAN BAPTISTE ADOLPH LA JEUNESSE.
